United States Patent Office

Des. 227,543
Patented July 3, 1973

227,543

WASTE BIN

Denis Austin Lamb, Elsinore Garage, Upper Park Road,
Bromley, England, and Julian Kerry Phillimore, 13
Benhurst Court, Streatham Common, London, England

Filed July 21, 1971, Ser. No. 164,967

Claims priority, application Great Britain Jan. 22, 1970

Term of patent 14 years

Int. Cl. D7—07

U.S. Cl. D7—193

FIG.1

FIG.2

FIG.3

FIG.4

FIG.3

FIG. 1 is a side elevational view of a waste bin showing our new design;

FIG. 2 is a rear elevational view thereof;

FIG. 3 is a perspective view; and

FIG. 4 is an exploded perspective view.

Portions of the drawing in FIGS. 3 and 4 are diagonally shaded to indicate transparency of the frontal panels overlaying opaque inner panels, not shown.

We claim:

The ornamental design for a waste bin, substantially as shown and described.
